MACHINE FOR CANCELING LETTERS.

No. 896,284.

Specification of Letters Patent.

Patented Aug. 18, 1908.

Application filed February 21, 1906. Serial No. 302,310.

To all whom it may concern:

Be it known that I, SAMUEL J. EVANS, a citizen of the United States, residing at Roanoke, Virginia, have invented certain new and useful Improvements in Machines for Canceling Letters, of which the following is a specification.

My invention relates to machines for canceling and post marking letters, my object being to improve the machine throughout and render its operation certain and effective.

The invention consists of the features and combination and arrangement of parts hereinafter described and particularly pointed out in the claims.

In the drawing, Figure 1 is a plan view of the machine with the parts in normal position ready to receive the letters to be canceled. Fig. 2 is a plan view of the marking and impression means and the device associated therewith for registering the letter and timing the operation of the printing or marking means, showing at *z* a letter in the act of being canceled, and illustrating also devices associated with the marking and impression means for insuring the proper control of the letters. Fig. 3 is a detail plan view of parts shown in Fig. 2 in a different position showing how the letter is held when it has arrived at an improper time until the marking means has arrived in proper position to act thereon. Fig. 4 is a detail sectional view of the friction feed wheel for the letters, some parts being shown in elevation. Fig. 5 is a detail view of the impression roll or platen showing also the vibrator and means for operating the same and the supplemental guard and its operating means. Fig. 6 is a sectional view through the bed of the machine from front to rear substantially on the line 6—6 of Fig. 1, with parts however shown in side elevation. Fig. 7 is a rear elevation of the machine. Fig. 8 is a detail view of the means for setting the stacker. Fig. 9 is a detail front view of the controlling gate for the letters and parts associated therewith.

The letters to be canceled and post marked are placed on edge upon a table 1, with their forward ends resting against the guard or guide wall 2, extending vertically in relation to the table surface. They are pressed against the feed wheel 3, which is in constant

rotation and thereby they are forced one by one into engagement with a friction feed wheel 4, against which it is guided and pressed by a spring finger 5 curved as shown in Fig. 1 to provide a flaring inlet for the letter. This spring pressure finger is pivoted at 6 to a lug on the guard wall 2, and it is pressed by a spring 7 attached thereto and to a bracket 8 so that its rounded or curved end is pressed constantly towards the friction feed wheel 4. A set screw 8^x acts as a stop for the spring pressure finger. The friction feed wheel is of special construction and is shown in detail in Fig. 4, and it consists of rubber rings 9 held to the hub or core of the wheel between the flanges 10 and the heads or plates 11 screwed to the core or hub, said hub being loose on the rotating shaft 13 and borne upon frictionally by the plates or disks 12 keyed to the said rotating shaft and the upper plate 12 being borne upon by a spring 13 held within a cap 14 and adjusted as to tension by the nut 15 threaded on the end of the rotating shaft. The frictional contact between the plates 12 and the heads of the feed wheel is so adjusted by means of the spring and nut that when the letters being fed into the machine are momentarily arrested as will be herein-after described the feed means consisting of the rubber rings 9 will remain at rest and will not tear or buckle the letter, whereas when the letter is free to advance through the machine the frictional contact between the parts of the friction wheel will be sufficient to move the letter forward.

As will be noticed from Figs. 4 and 7 the rubber feeding surfaces or rings 9 are separated from each other and into the space 16 thus provided the spring finger 5 extends slightly when in normal position Figs. 1 and 3.

Opposite the feed wheel a letter retarding block 17 is arranged, this consisting of rubber pieces 19 fixed in sockets 19' of the block 17, one of said rubber pieces being provided for each of the feeding rings 9 of the friction feed wheel.

The spring finger 5 when pressed away from the feed wheel will recede into the space 20 of the retarding block and the relation of the parts is such that the spring finger will act on said letters and cause them to be

pressed against the feed surface 9, and they will pass freely forward over the smooth rounded surface of the spring finger, but a second letter on presenting itself to the 5 spring finger 5 and the feed wheel while the first is still there, will, by its added thickness press the spring finger back so far as to cause it to recede into the space 20 of the retarding or separating block and thus ex- 10 posing the rubber retarders 19 to engage the second letter and hold it until after the first letter has been fed forward, when the spring finger will immediately press the second letter against the feed wheel 4 and away 15 from contact with the retarding blocks or rubbers 19. In this way the letters are separated and fed forward one by one. This retarder or separator 17 is supported upon a standard or arm 17' passing up 20 through an opening 17" in the bed of the machine from a lever 17^x pivoted below the bed at 17^a, Fig. 1, a spring 17^b acting on said lever and pressing the separator constantly towards the feed wheel, its move- 25 ment in that direction however being limited by the stop consisting of a screw rod 17^c journaled beneath the bed and operated by a finger piece 17^d. This yielding quality of the separator or retarder and also of the 30 spring finger 5 accommodates letters of different thickness.

From the feed wheel 4 the letters pass between the feed rollers 21, 22, of which 22 is a driven wheel while 21 is merely a presser 35 wheel, and from these the letter is fed forward to the impression means which comprises the rotary die or head 23 and an impression roller or platen 24. The rotary die or head carries the marking dies 25 for 40 applying the post marks and it also carries the ribs 26 for applying the canceling marks to the letters. Ink is applied to the dies and canceling ribs by an inking roller 27 having a textile covered periphery 28^x saturated 45 with ink which is applied to the dies and ribs each time they come around thereto.

The impression roller or platen is moved towards the die roller or head when a letter has arrived in proper position between them 50 so as to register properly with the canceling ribs and the die on the said roller. For securing this registration of the letter in relation to the means to make the impression, I employ a registering device or stop which 55 also acts as a timer for the operations of the impression roller or platen by locking the said platen to its operating mechanism at the proper times. This combined letter stop and locking-key consists of a lever 28 60 pivoted at 29 to the overhanging portion 30 of a box or bracket 31 secured to the bed of the machine. This lever has one arm 32 extending normally across the path of the letter between the die head and impression roller and 65 the other arm 33 of this lever extends later-

ally from the housing or bracket 31 to be at times in the path of the lug or shoulder 34 on the vibrator or controller 35 arranged independently and to one side of the impression platen or roller. This vibrator oscillates so as to carry the shoulder 34 from the position shown in Fig. 1 to that shown in Fig. 3 and back again. The locking-key or timing stop 28 is held normally out of the path of movement of the vibrator by a spring 35^x attached at one end to the locking-key and at the other to a bracket 36 on the housing. When however, a letter is fed between the printing and canceling members as at x Fig. 2 it contacts with the arm 32 of the letter stop or timer and swings the same on its pivot from the position shown in Fig. 1 so that its arm 33 will move out into the path of the shoulder 34 on the vibrator and this arm will be moved forward with the forward movement 75 of the vibrator which will result in the impression roller being moved forward to force the envelop or letter into contact with the canceling ribs on the die or rotary head and in proper register with said ribs. This result is accomplished as follows: The impression roller has its shaft journaled in a box 37 80 slideable in an opening 38 in the bed. The lower end of the impression shaft is pivoted to the frame at 39 and it is driven through a gear 96 fixed to said shaft. The upper end of the shaft extends into an opening in bar 41 85 which is arranged within a barrel or plunger 42 slidably mounted in the housing or box 31 before mentioned. This barrel has its forward end flattened and carries a pin 43 extending upwardly in front of the arm 33 of the letter registering stop and locking-key. Now when a letter has arrived at the registering-stop the said stop by pressure of the 90 letter will be turned on its pivot as above referred to so that its arm 33 will be struck by the said shoulder 34 and said arm will be moved forward and in this movement it will press upon the pin 43 and through it the 100 barrel 42 and the bar 41 carried thereby will 105 be moved to cause the impression roller to advance and press the letter upon the marking devices on the die or rotary head 23, which letter has, by contacting with the arm 110 32, been properly registered in place. As above stated the registering stop for the letter has swinging movement only, its pivot 29 being a fixed point on the housing or box 31 and in the swinging movement above described the registering stop for the letter acts as a locking-key to lock the impression roller with its actuating mechanism, and further, as it continues to swing under pressure due to the advancing movement of the shoulder 34 in the arrow direction Fig. 3 the end of its arm 32 is caused to recede from across the path of the letter and out of contact with the said letter which is thus left free to be 115 moved onward by the combined action of 120 125 130

the impression roller and the marking die or roller, it being post-marked and canceled during its passage between said parts.

The full throw of the platen or impression roller towards the die or marking roller or head is such as to mark the letters of minimum thickness and in order to mark thicker letters I have provided means whereby the impression roller may yield when a thicker or heavier letter is going through the machine. For this purpose the bar 41 is shouldered at 44 where it is borne upon by a comparatively stiff spring 45 arranged within the barrel 42 and resting at its rear end upon the 15 end 46 of the barrel. The spring is sufficiently stiff to cause the bar 41 and the platen or impression roller connected therewith to be moved forward as one body when the barrel or plunger is moved forward by the vibrator and locking-key 28, but when extra thick letters are going through the spring 45 will yield and allow the bar 41 to lag behind the plunger or barrel sufficiently to accommodate this extra thickness of the 20 letters. The bar 41 may be adjusted to set the impression roller or platen accurately in position by the nuts 47 on the threaded rear end of the bar.

It will be understood that the vibrator is 30 timed to advance the shoulder 34 in a certain relation to the arrival of the marking devices of the die at the printing point, and as the die carrier or rotary head has two sets of marking devices disposed thereon the vibrator 35 makes two complete oscillations to each revolution of the marking die carrier. Should a letter arrive at the registering stop arm 32 at an improper time it will be held either by the said stop arm or by a supplemental guard or 40 stop 48 arranged adjacent to but in a lower plane than the registering stop arm 32.

Fig. 3 illustrates the arrival of a letter at the registering stop at an improper time, that is for instance after the shoulder 34 of the 45 vibrator has advanced in the arrow direction beyond the point at which it might engage the end of the registering stop arm 33. At this time it will be noticed that the end of said arm 33 bears upon the plain periphery 50 of the vibrator which thus holds the registering stop against movement and with its end maintained across the path of the letter to hold the same until such time as the vibrator moves back and picks up the registering stop 55 or locking-key on its next forward movement, which will thus act to make the registering stop get in time with the marking roller and cause the letter to be registered with the marking devices and causing also the impression roller to be advanced at the proper moment. The other contingency that must be 60 guarded against is when a letter arrives and contacts with the main registering stop 32, when the vibrator is on its backward stroke 65 opposite to the direction indicated by the ar-

row, or when the vibrator is beginning its forward movement and has not yet arrived with its shoulder to the point of contact with the locking-key. The registering stop would be pressed aside freely towards the right when 70 the shoulder 34 had passed rearwardly in relation to the locking-key and it would allow the letter to be carried on through the machine, or to become misplaced in relation to the marking devices, by contact with the rotary die or marking head. In order to prevent the passage of the letter by the printing or canceling members at this time the supplemental stop or guard 48 above mentioned is employed, which has an end adapted to 75 reach across the path of the letter and act in connection with a gate 49 to hold the letter and prevent it from unduly acting against the registering stop or locking-key and slipping past the same until said locking-key is 80 engaged by and under the control of the shoulder on the vibrator. This supplemental stop or guard is oscillated from the position shown in Fig. 1 where it is in contact with the gate 49 to the position shown in 85 Fig. 2 in dotted lines, where it is swung back to allow the letter to pass by the marking devices and the registering stop. The opening of the guard or supplemental stop 48 to the position shown in dotted lines in Fig. 2 is but 90 momentary as it returns quickly to the position shown in full lines in said figure, the effect of which is to push the letter off from engagement with the hook end 32^x of the arm 32 on which it might hang. 95

The gate 49 is yieldingly held so that it will recede under the pressure of the letters and more or less according to their thickness. The gate is pivoted at 50 to a bracket 51 and it is pressed by a spring 52 so that its free end is yieldingly pressed away from the periphery of the die head. Its position is limited by a stop screw 53. The gate is shouldered at 54 and when the parts are in position to arrest the free passage of a letter in 100 order to register it with the marking devices the end of the supplemental stop or guard reaches around the corner of said shoulder and bears upon its face. The spring gate is also recessed at 55 to receive the end of the letter registering stop arm 32. This gate contacts with both the letter registering stop arm 32 and the supplemental guard 48 to prevent the letters slipping by the ends of said parts as it confines the letters closely by contact 105 with their sides as shown in Fig. 3. After passing the marking die and impression roller or platen the letters pass between the delivery rolls 56 and thence to a stacking device 57 carried by the shaft 58, said stacker having a scroll formation as shown in Fig. 1 and having an abrupt drop or shoulder 59. This scroll shaped stacker operates through a fence or shield 60 and the letters arriving from the delivery rolls strike the periphery thereof 110

100

120

125

130

and are pressed laterally and stacked against the plate 61 which is carried by or supported upon the block 62 supported on the table or chute 63 and which plate is movable along 5 the said chute as the quantity of letters stacked thereagainst increases. The ends of the letters after passing by the stacker strike against the fence or wall 64 extending at an 10 inclination over the table or chute and adjustably held by the slotted bracket and set screw 65—66.

The stacker is composed of a number of sections or scrolls Fig. 6 like that shown in plan in Fig. 1 carried by the said shaft 58. 15 The abrupt shoulder or drop 59 on the stacker allows the letters to contact with their forward edges close to the center of the rotary stacker and immediately the said letters are operated upon and pressed laterally 20 by the scroll portion of the stacker.

A supplemental stacker is arranged at 70 having a series of rounded projecting portions 71 to engage the extreme end portions of long letters and move them laterally. 25 This supplemental device being more particularly useful in the case of long letters.

Having now referred to the principal elements and the functions performed by them we will revert to the means for actuating 30 these elements.

The vibrator is oscillated by connections leading to an eccentric 72 on the main shaft 73 of the machine. These connections consist of the rotary shaft or pin 74 formed in 35 one piece with the vibrator head 35, the lower end of the said shaft bearing in a bracket or frame part 75 and having an arm or block 76 clamped thereto by the bolts 77, the said arm being connected by a right angular link 78 with the rod 79 of an eccentric strap 80 which is operated by the eccentric 72 on the main shaft 73 above mentioned. This eccentric rod has a yielding connection with the eccentric strap for which purpose 40 the said strap is formed with a hollow boss or barrel 81 receiving the enlarged head 82 of the eccentric rod against which a spring 83 bears at one end, the other end of said spring bearing upon a cap 84 screwed on to the boss 81. Through these connections the vibrator is oscillated so as to advance the shoulder 34 for the purpose of advancing the impression roll at the moment the marking device on the die carrier or marking head comes around 45 into marking position. The yielding connection is provided in order to hold the vibrator with its shoulder in advanced position and with the impression roller up to its work for a sufficient length of time to enable the marking device to make the impression on the letter it being noticed that the marking devices consisting of the ribs and the die associated therewith occupy a considerable portion of the circumference of the marking 50 head and it is therefore necessary to hold the

impression roller forward for the length of time occupied in the passage of the ribs and the die past the printing point and therefore the parts are so arranged that before the high part of the cam or eccentric arrives in line 70 with the axis of the eccentric rod the shoulder 34 will have advanced sufficiently to move the impression roller up to its work and this position will be maintained during the 75 passage of the high part of the cam by the axis of the eccentric rod and for an appreciable time after the said high part passes by the said axial line by reason of the employment of the spring 83 which allows the eccentric connection to yield under the greater 80 pressure resulting from the high part of the cam passing the axial line without doing damage or straining in any way the vibrator and the parts associated therewith.

The supplemental guard or registering stop 85 48 is connected with a sleeve 85 arranged to turn about the shaft or pin 74 and having an arm 86 extending laterally, from which depends a pin or rod 87, the lower end of which has an opening 88 receiving an eccentric rod 89 of an eccentric 90 which is also on the main shaft 73 and is connected with and operated in unison with the eccentric 72 above mentioned. This eccentric rod 89 is provided with a shoulder 90 adapted in the forward movement of the eccentric rod to strike the pin or rod 87 and thus turn the sleeve 85 so as to move the supplemental guard or stop 48 away from its normal position shown in Fig. 1 to the position shown in dotted lines in Fig. 2, immediately following which the shoulder 90 moves back and away from the pin or rod 87 and a spring 92 acting on the arm 86 immediately returns the supplemental guard or stop finger towards its normal position with the effects above described. 100

The main shaft 73 is driven in any suitable manner such as by a belt 93 and a pulley 94 and from this main shaft the shaft of the impression roller is driven through gearing 95, 110 96, as shown in Fig. 7. The friction feed wheel is driven by a gear 97 on its shaft 98, said gear being driven from a gear 99 on the main shaft. The feed roll 22 is driven by a gear 100 on its shaft meshing with the gear 101 on the main shaft. The feeding wheel 3 is driven from the shaft 98 of the friction feed wheel through the belt 102 and the pulleys 103, 104. In driving the delivery wheel 56 the gear 105 is loosely mounted on its shaft 106, said gear meshing with the gear 107 on the main shaft. There is another gear 108 on the shaft 106 of a different diameter from the gear 105 and meshing with the gear 99 and a clutch 109 is employed to connect 125 either of said gears to the shaft 106 in order to secure different speeds of the delivery rolls or wheels. The delivery rolls or wheels are geared together through the gears 110 120 and 111 on their respective shafts. In order 130

to drive the stacking device I provide a gear 112 on its shaft 113, said gear meshing with a gear 114 on the shaft or pin 115 and meshing with the gear 108. The supplemental device 70 is operated through a belt 116 and pulleys 117, 118.

The clutch 109 is operated by a fork 119 connected with a vertically movable rod 120 having at its upper end a handle 121 adapted to raise and lower the said rod with the fork to shift the clutch. The handle is provided with a boss 122 having a pin depending therefrom, marked 123, which in one position of the handle is adapted to rest on the stand 124 and support the clutch rod in an elevated position, whereas when the handle is turned to bring the pin 123 to an opening 125 in the said stand the pin dropping into said opening will allow the clutch rod to drop and shift the clutch from the upper gear to the lower gear, it being understood that the handle 121 may turn on the clutch rod in order to secure the above actions. The purpose of this change speed is to cause long letters to be drawn away from the marking or printing members more rapidly than the shorter letters thus preventing a second printing or marking action thereon at the rear end of the said long letter. This change of speed affects it will be noticed only the delivery rolls. One of these delivery rolls is pressed by a spring against the other. Its shaft is pivoted at the lower end at 126 while at its upper end said shaft is journaled in a box 127 Fig. 1, connected with a stem 128 extending into a casing or box 129 on the under side of the bed, said stem being pressed by a spring 130 within said casing. When the speed is changed as above to suit long letters the stacker must also be adjusted so that its action will be in proper time with the arrival of the letter thereat. It will be understood that the stacker is timed in its movement so that as the letter is delivered from the rollers 56 and its front end arrives at the stacker, the abrupt shoulder or drop will be presented to the letter while the other letters which were previously fed have been pushed or stacked laterally and are being borne upon by the high part of the stacker leaving thus a wide space between the stacked letters and the fence 60 for the reception of the next letter which moving into the open side of the scroll *i. e.* at which the abrupt shoulder is located, will by the rapid rotation of the stacker immediately press the newly arrived letter laterally for the stacking operation.

Now when long letters are to be operated on and the speed of the delivery rolls is changed as above described the stacker must be adjusted so that its open side will be presented to the newly delivered letter at the proper moment and for this purpose the stacker is loosely mounted on its shaft which 65 shaft is provided with a collar 130^x which

may be raised slightly by the handle 130, fixed on the same, to disengage the pin 131 of said collar from the hole 132 in the stacker, after which the stacker may be turned to bring another hole 133 below the pin 131 70 whereupon the collar may be dropped and the said pin will then connect with the stacker in the new position to which it has been adjusted for long letters. The collar is splined to the shaft and a spring 130^y presses it down, 75 said spring bearing against a nut 130^z screwed onto the shaft.

Referring now to certain details of construction: A guide strip 134 extends along the pathway of the letters, which guides 80 them from the feed rolls to the marking members and thence to the delivery rolls. A spring guide 135 is also used for this purpose and a guide 136 for a similar purpose is attached to the bracket 51 and extends over one of the delivery rolls. The impression roller after being advanced is retracted by the spring 138, dotted lines Fig. 1, attached below the table and connected by a link 139 to a block 37, Fig. 5, in which the 85 shaft of the impression roller bears. This box extends up into the slideway or opening in the table top which permits the said impression roll to move towards and from the die carrier or rotary head. The forward 90 movement of the impression roller is limited to suit the thinnest letters by a stop collar 142 on the sliding barrel 42 striking against the rear end of the housing. The return movement of the locking key or letter registering stop is limited by a stop 141 on the 95 fixed housing 31.

The inking roller 27 is of special construction represented in Fig. 5. The fabric covering its periphery is held in place between 100 the flanges 143 which are screwed to the block 144. This block is faced peripherally with rubber 145 upon which the fabric or felt periphery bears. The rubber surface prevents the fabric from creeping or piling up at any one point. This inking roller may be set towards or from the die and canceling 105 rib carrier for which purpose its pin 145^x extends up through an opening 146 in the table top and it is carried by a lever 147 pivoted at 148 to the bottom of the table and pressed by a spring 149. An adjustable stop limits the position of the said inking roller towards the marking head or printing 110 roller 23.

Referring now to the eccentrics for driving the vibrator and the supplemental guard or stop finger it will be seen from Fig. 6 that these eccentrics are connected by a sleeve 115 loose on the main shaft, the eccentric 90 being attached to said sleeve by a screw 150 while the eccentrics 72 is formed in one piece with the said sleeve. These eccentrics are driven through a gear 151 loose on the main 120 shaft but connected to the lower eccentric 130

72 by the screw 152. This gear meshes with a gear 153 turning on a pin 154 of a bracket 155, said gear 153 being attached by a sleeve 156 with a gear 157 which is driven 5 by a gear 158 fixed on the main shaft. This gear train gives a two to one movement of the vibrator, impression roller and supplemental stop in relation to the rotary marking head which latter as above described, 10 carries two sets of marking devices.

An important feature of my invention is the yielding bearing point or block 34' at the shoulder 34 of the vibrator. This block is guided to recede within the head and thus 15 afford a yielding bearing should the point of the shoulder 34 meet the end of the arm 33 at such an angle to jam or damage the parts. This block 34' projects slightly at the point of the shoulder and will yield and prevent 20 damage to the parts under certain conditions. The block is pressed by a spring 34" and it is limited in its outward movement by a pin 34^a passing through the head 35 and a slot 34^b in the block.

25 I claim as my invention:

1. In a machine of the class described the platen, a marking head, an impression roller, a combined letter-registering-stop and locking-key and an oscillating vibrator supported independently of the movable support of the platen and arranged to engage the locking-key for advancing the impression roller, substantially as described.

2. In a machine of the class described, a 35 marking head, an impression roller, a combined letter-registering-stop and locking-key, and an oscillating vibrator supported to one side and independently of the impression roller and having a shoulder to engage the 40 locking-key, said locking key bearing against

the plain periphery of the vibrator when pressed by a letter at an improper time, substantially as described.

3. In combination with the marking head, an impression roller, a combined letter-registering-stop and locking-key supported on a pivot independently of the movable support of the platen or impression roller, and an oscillating vibrator also supported independently of the said movable support of the 50 platen, said locking key having movement to and from the path of the vibrator substantially as described.

4. In combination with the marking head, an impression roller or platen, a combined 55 letter-registering-stop and locking-key, an oscillating vibrator for operating the locking-key, and a yielding bearing portion carried by the said vibrator, substantially as described.

5. In combination, the marking head, a platen, the locking-key operated by a letter, an oscillating vibrator to operate the locking-key to move the platen, and means for driving the marking head and vibrator in a one 65 to two relation, said marking head carrying two sets of marking devices.

6. In combination, the marking head, a platen, a letter-registering-stop and locking-key combined, an oscillating vibrator having 70 a shoulder to operate the locking-key, a supplemental stop and a sleeve carrying the same and arranged concentric with the axis of the vibrator, substantially as described.

In testimony whereof, I affix my signature 75 in presence of two witnesses.

SAMUEL J. EVANS
